Primary Examiner — Steven J Czyz

(57) **CLAIM**

The ornamental design for a manual breast pump capsule, as shown and described.

DESCRIPTION

FIG. 1 is an isometric view of a manual breast pump capsule in accordance with my new design;

FIG. 2 is a front elevation view thereof;

FIG. 3 is a back view thereof;

FIG. 4 is a side view thereof;

FIG. 5 is a side view thereof, for the side opposite that of FIG. 4;

FIG. 6 is a top elevation view thereof;

FIG. 7 is a bottom elevation view thereof;

FIG. 8 is a perspective view of the manual breast pump capsule, shown open with environment;

FIG. 9 is an isometric view of a second embodiment of the manual breast pump capsule;

FIG. 10 is a front elevation view thereof;

FIG. 11 is a back view thereof;

FIG. 12 is a side view thereof;

FIG. 13 is a side view thereof, for the side opposite that of FIG. 12;

FIG. 14 is a top elevation view thereof;

FIG. 15 is a bottom elevation view thereof;

FIG. 16 is a perspective view of the manual breast pump capsule, shown open with environment;

FIG. 17 is an isometric view of a third embodiment of the manual breast pump capsule;

FIG. 18 is a front view thereof;

FIG. 19 is a back view thereof;

FIG. 20 is side view thereof;

FIG. 21 is a side view thereof, for the side opposite that of FIG. 20;

FIG. 22 is a top elevation view thereof;

FIG. 23 is a bottom elevation view thereof; and,

FIG. 24 is a perspective view of the manual breast pump capsule, shown open with environment.

The broken lines depict portions of the article and environment that form no part of the claimed design.
